UNITED STATES PATENT OFFICE.

ALLEN S. WISE, OF PITTSBURGH, PENNSYLVANIA, ASSIGNOR TO WESTINGHOUSE ELECTRIC & MANUFACTURING COMPANY, A CORPORATION OF PENNSYLVANIA.

CENTERING DRIVE FOR WASHING MACHINES.

Application filed May 22, 1924. Serial No. 715,104.

My invention relates to washing machines and has special relation to drive mechanism therefor.

An object of my invention is to provide 5 a power drive for a washing-machine tub that shall be actuatable on movement of a control member to bring the tub to a normal position and automatically stop it in this position.

10 Another object of my invention is to provide a drive mechanism for a washing-machine tub which shall be operative, when a clutch is in one position, to impart a washing movement to the tub and, when the clutch 15 is in another position, to restore the tub to a normal inoperative position.

A further object of my invention is to provide power means for gradually initiating and increasing the movement of a tub with- 20 out sudden and destructive shock.

A still further object of my invention is to provide a washing-machine drive having the aforementioned characteristics and being of special simplicity.

25 A still further object of my invention is to provide a single extensible control member for a washing machine.

Reference is had to the accompanying drawings in which.

30 Figure 1 is a side elevational view of a machine embodying my invention, a wall of the cabinet being partially broken away to reveal the drive mechanism.

Fig. 2 is an end elevational view of the 35 drive mechanism, parts being broken away.

Fig. 3 is a sectional view of the drive mechanism taken on the line III—III of Fig. 1.

Fig. 4 is a detail sectional view taken on 40 the line IV—IV of Fig. 3, the gear case being removed and parts being broken away.

Fig. 5 is a detail sectional view taken on the line V—V of Fig. 3, showing the relationship of parts when in operative position, and

45 Fig. 6 is a view, similar to Fig. 5, showing the relationship of parts when the tub is in normal stopped position.

In the cabinet 1, a motor 2 is secured having a motor shaft 3 journalled in a gear case 4. A worm 5 on the motor shaft meshes 50 with a worm gear 6 which is free on a shaft 7 journalled in the case 4. The worm gear 6 is rigid with a bevel gear 8. The bevel gear 8 meshes with a bevel gear 10 on a 55 wringer drive shaft 11 which is journalled in

the case 4 and drives the rolls 12 of a folding wringer 13 by means of mechanism described and illustrated in my copending application filed June 17, 1924, Serial No. 720,529, and assigned to the Westinghouse Electric and 60 Manufacturing Company.

The bevel gear 10 meshes with a third bevel gear 14 free on the shaft 7. The bevel gears 8 and 14 have clutch faces 15 and 16, respectively, thereon, engageable by a clutch collar 17 slidably by a clutch yoke 18 along the shaft 7 and splined thereto.

The clutch yoke 18 is movable by a rotative control rod 20 journaled in the case 4 and extending adjacent the top of the cabinet portion 1, terminating in a square end 70 received in an opening in a handle 21.

The handle 21, in one position thereof, projects above the top of the cabinet portion 1 and is held in that position by a spring-urged ball 22 received in one of a pair of recesses 23 in the end of the control rod 20. The handle may be moved downwardly, causing the ball 22 to be received in the lower recess, in which position the handle is below 80 the top of the cabinet portion 1.

At the end of the shaft 7, an inner eccentric 24 is secured, having a recess 25 therein and surrounded by an outer eccentric 26 having a recess 27 therein, the recess 25 receiving a roller 28. The outer eccentric 26 is received in the end of a connecting rod 30 having a flange 31 thereon and a cap 32 for maintaining the eccentrics in place.

The connecting rod 30 is pivoted to a rock arm 33 rigid with a shaft 34 journalled in a support 35 secured to the gear case 4 and the cabinet portion 1. A rock lever 36 is rigid with the shaft 34 and has a slotted upper end engaging a pin 37 on a tub 38 95 which is provided with a trunnion 40 in a bearing 41 supported by the cabinet portion 1.

In the normal operation of the device, the motor 2 rotates the shaft 3, the worm 5, the worm gear 6 and the bevel gear 8. This imparts, through the bevel gear 10, rotation to the wringer drive shaft 11. The clutch collar 17 is, at this time, in engagement with the clutch face 15 of the bevel gear 8 105 and transmits power to the shaft 7 which rotates the inner eccentric 24 in the direction indicated by the arrow in Fig. 5.

The roller 28 is at the ends of the recesses 25 and 27 and transmits rotary movement 110

to the outer eccentric 26, which actuates the connecting rod 30 and moves the rock arm 33, the shaft 34, the rocking lever 36 and the tub 38.

5 By the expression "normal inoperative position of the tub", that position is designated which the tub occupies when it is stopped so that the removal of clothes or fabrics therefrom and the placing of other 10 articles or materials therein is permitted.

When it is desired to restore the tub to normal inoperative position, the operator rotates the handle 21 and the control rod 20 and throws the clutch collar 17 into en-

15 gagement with the clutch face 16 of the bevel gear 14. This causes a reversal of the direction of rotation of the shaft 7 without interfering with the continued rotation in its original direction of the wringer drive

20 shaft 11. The rotation of the shaft 7 in its opposite direction transmits rotary movement to the inner eccentric 24 in the direction indicated in Fig. 6.

The reversed movement of the inner eccentric 24 is not immediately transmitted to the outer eccentric 26, and relative movement between the eccentrics occurs until the roller 28 reaches the ends of the recesses 25 and 26, as shown in Fig. 6. Further 30 movement of the inner eccentric 24 with respect to the outer eccentric 26 is then impossible and the outer eccentric is concentric with the shaft 7.

At this time, the tub 38 is in its normal 35 inoperative position. Continued rotation of the shaft 7 does not then cause an oscillation of the tub 38 but prevents movement thereof.

It will be noted that the relative movement between the inner eccentric 24 and the outer eccentric 26 takes place through substantially 180°. In other words, substantially a 180° relative movement is necessary to change the outer eccentric 26 from full 45 eccentricity to concentricity with the shaft 7. It is obvious, therefore, that the tub 38, irrespective of its position at the time, will be brought to rest in one half of a rotation of the shaft 7.

50 After the tub 38 has been brought to rest, the rotation of the shaft 7 continues and the wringer drive shaft 11 is maintained in operation. There is, however, no movement of the connecting rod 30 or the rock lever 36.

55 When the tub 38 is moving in normal washing operation, the clutch collar 17 may, if desired, be thrown in neutral, thus disconnecting power from the shaft 7 and bringing the tub 38 to rest.

60 To start the oscillation of the tub, when it is in inoperative condition, the clutch collar 17 is shifted, in an obvious manner, to engage the clutch face 15 of the bevel gear 8, and rotation of the inner eccentric 24 in 65 the direction indicated by the arrow in

Fig. 5 is initiated. Relative movement between the inner eccentric and the outer eccentric 26 then occurs, which is communicated to the connecting rod 30 at the time of initiation of its movement. The eccentricity of the outer eccentric 26 is zero and this eccentricity gradually increases. It is apparent, therefore, that the motion of the connecting rod 30, which is due to the eccentricity of the outer eccentric 26, 75 is gradually initiated. The connecting rod 30 is, however, brought up to full speed and full movement in one half of a rotation of the shaft 7.

The invention is not limited to the specific details of construction and operation of the embodiment illustrated and described which may be extensively modified and varied without departing from the spirit of the invention.

Instead of the tub 38, a container of some other types may be substituted in certain applications of the invention. The invention may also be applied to washing machines of the dolly and vacuum-cap types and, in fact, may be used for moving washing elements of a widely diversified nature.

A substantial range of equivalents is contemplated within the scope of the appended claims.

I claim as my invention:

1. The combination of a container mounted for movement, drive means for moving said container, means for reversing the direction of said drive means, and means operative upon the reversal of said drive means to move said container to normal position and stop it in that position.

2. The combination of a container mounted for movement, a shaft, an inner eccentric on said shaft, and outer eccentric surrounding said inner eccentric, connections between said outer eccentric and said container for moving said container, and means for reversing the direction of rotation of said shaft for altering the relative angular positions of said eccentrics, decreasing the eccentricity of said outer eccentric and stopping said container.

3. The combination of a container mounted for movement, a shaft, a gear free on said shaft, means for rotating said gear, a second gear meshing with the first mentioned gear, a third gear free on said shaft and meshing with said second gear, a clutch secured for sliding movement on said shaft and engageable with said first mentioned gear or said third gear, an inner eccentric on said shaft, an outer eccentric surrounding said inner eccentric, and driving connections between said outer eccentric and said container, said eccentrics being relatively movable for a limited distance whereby, upon the rotation of said shaft in one direction, when said clutch is engaged with the first mentioned

gear, said container is given a normal operative motion, and, on the rotation of said shaft in a reverse direction when said clutch is in engagement with said third gear, the eccentricity of said outer eccentric is decreased.

4. The combination of a washing machine tub mounted for movement, power means for moving said tub, a rod for controlling said power means and a handle portion slidable along said rod from an operative position to inoperative position and vice versa.

5. The combination of a cabinet portion, a tub, drive means for moving said tub and an extensible rod for controlling said drive means extending above the top of said cabinet portion but movable downwardly in a straight line below the top thereof.

6. The combination of a cabinet side, a tub mounted for movement, drive means for said tub including a clutch, a rod for controlling said clutch, and a handle for moving said rod, said handle being movable into operative position by the mere movement upwardly above the top of said side and movable below the top of said side.

7. The combination with a shaft, of an eccentric member rotatable therewith, a ring on said eccentric member eccentric with respect to said shaft during rotation thereof in one direction, structure operatively associated with said ring and operated thereby upon rotation of said shaft in said one direction, and means operative upon rotation of

said shaft in reverse direction for decreasing the eccentricity between said shaft and said ring.

8. The combination with a shaft, of an eccentric member rotatable therewith, a ring on said eccentric member eccentric with respect to said shaft during rotation thereof in one direction, structure connected to said ring and operated thereby upon rotation of said shaft in said one direction, and means comprising a loose connection permitting relative movement between said eccentric member and ring and operative upon rotation of said shaft in reverse direction for decreasing the eccentricity between said shaft and ring.

9. The combination with a container mounted for oscillatory movement and a wringer drive shaft, of a power-driven shaft, means effective upon rotation of said shaft in one direction for moving said container toward and from normal inoperative position and for rotating said wringer drive shaft, means for reversing the rotation of said power-driven shaft, and means effective upon said reversal to maintain the unidirectional rotation of said wringer drive shaft and to stop the movement of said container in the normal inoperative position thereof.

In testimony whereof, I have hereunto subscribed my name this 6th day of May 1924.

ALLEN S. WISE.
